UNITED STATES PATENT OFFICE.

HENRY LYSHOLM, OF WOODBURY, NEW JERSEY.

MECHANISM FOR FEEDING SHEET METAL TO PUNCHING-MACHINES.

1,221,881

Specification of Letters Patent. Patented Apr. 10, 1917.

Application filed March 17, 1916. Serial No. 84,775.

To all whom it may concern:

Be it known that I, HENRY LYSHOLM, a citizen of the United States, and resident of Woodbury, county of Gloucester, and State 5 of New Jersey, have invented an Improvement in Mechanism for Feeding Sheet Metal to Punching-Machines, &c., of which the following is a specification.

The object of my invention is to provide 10 means for feeding and handling sheet metal plates in connection with a punching machine or other means for performing work upon the sheet along its length. More particularly, my invention has special utility in 15 feeding long sheet steel, such as used in ship building, to the punching machine for punching rivet holes therein along its length 20 and transversely to the length, according to requirements; and whereby the manipulation 25 of the plates may be easily and accurately accomplished by a single operator.

The general construction of my invention comprehends a long sheet supporting carriage adapted to run upon tracks or guides 25 in a direction transversely to the length of the sheet supported thereby and arranged to have its movements controlled by the operator, who preferably stands or sits upon the carriage and remains in position in front of 30 the punching machine; the said carriage provided with means for supporting the long sheets to be punched and feeding the same longitudinally of the carriage and in the direction of their length; further, in an organized machine of the character above 35 stated, when provided with manually controlled means for insuring the proper positioning of the sheet under the punching die; and in addition to the above defined features, a further improvement having capacity 40 for raising and lowering the sheet in respect to the punching devices under the control of the operator.

My invention also comprehends details of 45 construction which, together with the features above set out, will be better understood by reference to the drawings, in which:

Figure 1 is a front elevation of a machine embodying my invention, with portions 50 broken away; Fig. 2 is a plan view of the same; Fig. 3 is a transverse section of the same taken on line $x-x$ of Fig. 2; Fig. 4 is a perspective view of a portion of the machine for controlling the time of operation

of the punching machine; Fig. 5 is a sectional view of the punch, stripper and sheet about to be punched; Fig. 6 is an elevation of a modified construction of my invention; and Fig. 7 is a sectional view of a portion of the same.

2, 2, are guide tracks, respectively at each side of the punching machine A; and 3, 3, are additional guide tracks, parallel to the tracks 2, 2, and widely spaced to support the distant portions of the carriage 4. The guide tracks 2, 2, are provided with racks 2^a, which are engaged by teeth 8 about the supporting and guide wheels 7 by which the middle portion of the carriage is sustained. The remaining guide wheels 6 are arranged near 70 the ends of the carriage and are grooved to run upon the guide rails 3. As shown, the carriage 4 has four of the guide wheels 7 and four of the guide wheels 6, the former by reason of their teeth engaging the racks, 75 insuring an equal and uniform movement of both ends of the carriage, and in this way properly controlling the presentation of the sheet being punched to the punching machine.

The carriage 4 consists of two main girder sections made up of the side girders 4^a and the connecting bracing parts 4^b, said sections united by the operator's platform 5 providing a gap 5^a in the continuity of the carriage 85 for permitting the carriage sections to pass upon either side of the punching machine A, as will be readily understood by reference to Fig. 2. As indicated, a seat 21 is provided upon the platform for the operator in 90 front of the punching machine A.

Immediately to each side of the punching machine and journaled upon the sections 4 of the carriage, are shafts 9, each carrying a plurality of feeding wheels 12, said shafts 95 and wheels being coupled to rotate in unison by means of the longitudinal shaft 15 and miter gears 14. This shaft 15 is intermittently rotated in either direction by a notched wheel 17 secured to the shaft and a lever and 100 detent 18 journaled on the shaft so that the detent may properly engage the notches in the wheel. The lever is provided with a handle portion by which it may be grasped and manually operated to rotate the shaft 105 15 in either direction with a step-by-step motion. A spring 18^a (Fig. 3) may be employed to counterbalance the lever and de-

tent and yieldingly hold it horizontal. In this way, a sheet resting upon the wheels 12 will be supported at a proper height to enter between the dies of the press A and be fed longitudinally with a step-by-step motion to position it each time a hole is to be punched. As the sheets are very long and require more support and moreover, as the sheet has, at the start of the punching operation, to be supported wholly at one side of the press, it is necessary to provide further means of support for the sheet. This additional supporting means consists of a plurality of parallel transverse shafts 9 and wheels 12, said shafts journaled at intervals along the length of each of the sections 4, 4, of the carriage, as is clearly shown. To insure more feeding friction upon the plate to be punched, I prefer that the two shafts 9, next to the punching machine and on each of the sections of the carriage, shall be mechanically connected so as to rotate in unison, and this I accomplish by a chain and sprocket wheel drive, as shown at 13. In this manner, the sheet is supported upon the various supporting and feed wheels 12 of one section 4 of the carriage, and by proper manipulation of the lever 18, may be fed forward longitudinally of its length to positions suitable for punching by the press A. As the sheet passes on, its end will be received upon the supporting and feed wheels 12 upon the other section 4 of the carriage; and finally, when the whole length of the sheet has been punched, it will have left the wheels 12 upon which it was first supported and rest upon the wheels 12 at the opposite side of the press. The extent of feeding of the sheet at any moment is governed by the distance between the holes to be punched and the manner of determining this will be explained later on in the specification.

The movements of the carriage upon the guiding tracks to adjust the sheet to be punched transversely to the length of the sheet is accomplished as follows: Toothed wheels 7 of each of the tracks 2, 2, are connected together by a shaft 29 whereby they are caused to rotate in unison, and said shaft is provided with manually controlled means for rotating it, said means comprising a notched wheel 19 loosely journaled upon the shaft 15 and connected with shaft 29 by a chain and sprocket wheels 16, said notched wheel adapted to be intermittently rotated by a hand operable lever 20 hinged to shaft 15 and provided with a detent device to engage the notches of the wheel. This lever 20 may be counterbalanced by a spring 20^a to hold it yieldingly in horizontal position, similarly to what is shown in Fig. 3 in respect to lever 18. In this manner the operator may impart a rotation to the shaft 29 in either direction and thereby shift the carriage as a whole upon the guide tracks when

it is desired to punch a series of holes in the sheet transversely to the length of the sheet. In this operation, it is manifest that, as the sheet must be fully shifted back through the overhang of the press A to insure punching the holes near the edge of the sheet nearest the operator, the carriage will have capacity for being moved back relatively to the punching machine for a corresponding distance and will require the opening 5^a from the rear to receive the punching machine to permit such operation. Because of the necessity of this break in the continuity of the carriage in the direction of its length, the platform 5 acts as a joinder of the sections 4, 4, and is projected to an extent to give ample strength and space upon which to arrange the operative parts for controlling the movements of the carriage and the sheet feeding mechanism thereof.

As it is essential that the operator shall control the time of action of the punching machine A, a suitable controlling device therefrom to the operator's platform 5 is provided, and this device may be made in the form shown. This mechanism comprises a shaft 30 journaled on the platform 5 and provided with a foot treadle 31. This shaft extends backward parallel to the rails 2, and is guided in suitable bearings 32 on the punching machine base, and may be square in cross section to operate a trip arm B through which it passes. Any other suitable means for putting the punching machine into operation may be employed in lieu of that shown and I do not limit myself in this respect.

In the foregoing description I have referred to the means for moving the sheet carrying devices in a horizontal plane to position the sheet at definite places under the punching die of the punching machine, and I will now describe the means for adjusting the sheet transversely to the plane of its surface to insure proper engagement of the punch with indented portions of the plate surface. Referring to Fig. 5, it will be seen that the surface of the sheet or plate E is depressed or center punched as at F, there being one of these depressions at every spot where a hole is to be punched. These positions of these depressions are insured by use of a templet or by laying out their positions by measurements upon the sheet itself. The punch C of the punching machine A is provided on its bottom at its center with a conical projection which will enter the depressions F of the sheet when brought into alignment, as shown. In practice the punch C is held in the machine with slight vertical freedom of play so that it may rest upon the sheet and its point drop into the recess F when the sheet is properly moved under it. D is the stripper to remove or strip the punched sheet from the punch after

the hole has been made and the punch is being withdrawn. To insure coöperation between the sheet and the punch in positioning the former to the latter, it is necessary 5 to provide means for raising and lowering the sheet. This is accomplished by providing hinged frames 22 in which the shafts 9, 9, next to the punching machine are journaled and employing means under the control of the operator to move said frames 10 about their hinges 23 to raise or lower the shafts 9 and their feeding and supporting wheels 12. This means comprises a shaft 24 at each side of the platform 5 and respectively journaled in the side frames of the 15 two sections 4, 4, of the carriage. These shafts 24 have arms 25 whose outer ends are connected by links 26 with the hinged frames 22. The shafts 24 are each provided 20 with a hand lever 27 for rocking them, said lever having a detent to engage the notched segment 28 secured to the platform. In this way the operator may manipulate either hand lever 27 as desired to raise or lower the 25 sheet supporting wheels 12 and the sheet carried thereby. When the wheels 12 adjacent to the punching machine have been raised so that the sheet E just supports the punch C, the shafts 24 are locked. Then 30 when the levers 18 and 20 are manipulated to shift the sheet the conical projection on the bottom of the punch will find the depressions F in the sheet when brought to alignment; and when this is done, the operator 35 will know the fact by the "feel," and he then presses the treadle 31 and operates the punching machine to drive down the punch die C. It will be understood that this vertical adjustment of the feeding wheels 12 40 and their supporting frames 22 is very slight and hence may be accomplished without disturbing the operative relation of the miter gears 14. When the vertical adjustment has been made to suit any given thickness of 45 sheet, it may ordinarily be maintained; but in some cases, at starting to punch the sagging end of a relatively thin sheet, it may be that the sheet will be required to be specially adjusted as to height at that end and 50 the same requirement may be equally necessary when finishing the punching at the other end of the sheet, but when the sheet is supported by the guide wheels 12 at both sides of the punching machine at the same 55 time the vertical adjustment first stated may be wholly relied upon.

Instead of adjusting the wheels 12 at each side of the punching machine vertically to properly level the plate to coöperate with 60 the punching die, the same result may be accomplished as shown in Figs. 6 and 7. In this case, the sections 4, 4, of the carriage are hinged at 32 to the sides of the platform 5; and the bearings 33 for the supporting 65 and propelling shaft 29 are eccentric and

journaled in the bearings 34 of the carriage sections as will be understood by reference to Fig. 7. The eccentric bearings 33 each have an arm 35 which is connected by a link 36 with the rocker arm and shaft 24 shown in the other figures. The handles 27^a (Fig. 6) may be adjusted to adjust the eccentric bearings to raise or lower the adjacent ends of the carriage sections 4, 4, upon their guide and supporting wheels 7. The sections 4, 4, 70, 75 may be adjusted on all of the supporting wheels 7 in the same manner and each section may be adjusted separately, thereby following the general plan of adjustment previously explained.

I do not confine myself to the details described for imparting the various movements to the parts, but have shown and described means which are excellently suited for the several requirements and they are by way of 80 example and not as restriction.

It will now be apparent that I have devised a novel and useful construction which embodies the features of advantage enumerated as desirable, and while I have in the 90 present instance shown and described the preferred embodiment thereof which has been found in practice to give satisfactory and reliable results, it is to be understood that I do not restrict myself to the details, 95 as the same are susceptible of modification in various particulars without departing from the spirit or scope of the invention.

Having now described my invention, what I claim as new and desire to secure by Letters Patent, is:—

1. A machine for operating upon sheet metal, and a plurality of parallel guide tracks part of which are arranged at one side of the machine and part at the other 105 side, combined with a unitary carriage having supporting wheels guided upon the plurality of tracks and having a gap at one side to fit around the machine, a plurality of parallel shafts upon the carriage at each side 110 of the machine, a plurality of parallel narrow feeding wheels secured to each shaft for supporting the sheet to be operated upon, manually controlled means on the carriage for rotating the shafts and wheels which are 115 immediately at each side of the machine, and manually controlled means also on the carriage for feeding the carriage along the guide tracks, the entire operative means for the wheels and shafts and also for feeding 120 of the carriage being upon and moving with the carriage itself.

2. A machine for operating upon sheet metal, and a plurality of parallel guide tracks part of which are arranged at one side of the machine and part at the other 125 side, combined with a carriage having supporting wheels guided upon the plurality of tracks, said carriage having a gap at its side to fit around the machine, a plurality of 130

parallel shafts upon the carriage at each side of the machine, a plurality of parallel narrow feeding wheels secured to each shaft for supporting the sheet to be operated upon, 5 manually controlled means on the carriage for rotating the shafts and wheels which are immediately at each side of the machine manually controlled means on the carriage for raising and lowering the rotated shafts and wheels which are adjacent to the machine 10 for adjusting the level of the sheet supported by the wheels, and manually controlled means on the carriage for feeding the carriage along the guide tracks, the entire 15 operative means for the wheels and shafts and also for feeding the carriage being upon and moving with the carriage itself.

3. A machine for operating upon sheet metal, and a plurality of parallel guide tracks part of which are arranged at one 20 side of the machine and part at the other side, combined with a carriage having supporting wheels guided upon the plurality of tracks, a plurality of parallel shafts upon 25 the carriage at each side of the machine, a plurality of feeding wheels secured to each shaft for supporting the sheet to be operated upon, manually controlled means on the carriage for rotating the shafts and wheels which are immediately at each side of the 30 machine, manually controlled means for feeding the carriage along the guide tracks, and means forming a connection between the carriage and machine whereby the time of 35 action of the latter may be under the control of the operator on the carriage.

4. A machine for operating upon sheet metal, and a plurality of parallel guide tracks part of which are arranged at one 40 side of the machine and part at the other side, combined with a carriage having supporting wheels guided upon the plurality of tracks, a plurality of parallel shafts upon 45 the carriage at each side of the machine, a plurality of feeding wheels secured to each shaft for supporting the sheet to be operated upon, manually controlled means on the carriage for rotating the shafts and wheels which are immediately at each side of the 50 machine, manually controlled means for feeding the carriage along the guide tracks, manually controlled means for raising and 55 lowering the feeding and guide wheels at each side of the machine, and an operator's platform carried by the carriage in front of the machine and upon which all of the manually controlled means are grouped so as to be within easy reach of the operator without materially shifting his position.

5. A machine for operating upon sheet metal and a plurality of parallel guide tracks part of which are arranged at one side of the machine and part at the other side, in combination with a carriage supported and traveling upon said guide tracks 65

and extending on each side of the machine, the carriage having a gap in its side approximately midway of its length by which it is enabled to straddle the machine, a plurality of parallel shafts journaled on the 70 carriage at each side of its gap, a plurality of narrow supporting wheels upon each of the shafts a part of which wheels are arranged beyond the sides of the carriage, means coupling the shafts located immediately upon each side of the gap for rotating them, hand operable means on and movable with the carriage for operating said means for rotating the shafts and their wheels in either direction, and manually operable means for raising and lowering the shafts next to the gap in the carriage while leaving the remaining shafts and their wheels at the normal level. 75

6. A machine for operating upon sheet metal, and a plurality of parallel guide tracks part of which are arranged at one side of the machine and part at the other side, combined with a carriage having supporting wheels guided upon the plurality of 80 tracks, a plurality of parallel shafts upon the carriage at each side of the machine, a plurality of feeding wheels secured to each shaft for supporting the sheet to be operated upon, manually controlled means on the carriage for rotating the shafts and wheels which are immediately at each side of the 85 machine consisting of a shaft longitudinally of the carriage, gearing between the said shaft and the shafts of the manually controlled feeding wheels, a toothed wheel secured to the longitudinal shaft, and a hand lever and detent device for engaging the toothed wheel for rotating it in either direction with a step-by-step motion, and manually controlled means for feeding the carriage along the guide tracks. 90

7. A machine for operating upon sheet metal, and a plurality of parallel guide tracks part of which are arranged at one 100 side of the machine and part at the other side, combined with a carriage having supporting wheels guided upon the plurality of tracks, a plurality of parallel shafts upon 105 the carriage at each side of the machine, a plurality of feeding wheels secured to each shaft for supporting the sheet to be operated upon, manually controlled means on the carriage for rotating the shafts and wheels which are immediately at each side of the 110 machine, manually controlled means for raising and lowering the rotated shafts and wheels which are adjacent to the machine for adjusting the level of the sheet supported by the wheels, said means consisting of 115 pivoted arms in which the rotatable shaft is journaled, a rocking shaft, connection between the rocking shaft and the pivoted arms, a stationary rack having teeth, and a lever and detent device for rocking the rock 120 125 130

shaft and holding it in adjusted position, and manually controlled means for feeding the carriage along the guide tracks.

8. A machine for operating upon sheet metal, and a plurality of parallel guide tracks part of which are arranged at one side of the machine and part at the other side, combined with a carriage having supporting wheels guided upon the plurality of tracks, a plurality of parallel shafts upon the carriage at each side of the machine, a plurality of feeding wheels secured to each shaft for supporting the sheet to be operated upon, manually controlled means on the carriage for rotating the shafts and wheels which are immediately at each side of the machine, and manually controlled means for feeding the carriage along the guide tracks, said means for feeding the carriage consisting of a transverse shaft for rotating the supporting wheels, a notched wheel connected to rotate the rotatable shaft, a hand lever and detent for engaging the notched wheel and rotating it in either direction with a step-by-step motion.

9. A machine for operating upon sheet metal, and a plurality of parallel guide tracks part of which are arranged at one side of the machine and part at the other side, in combination with a long carriage structure extending laterally upon both sides of the machine and consisting of two girder sections connected by a platform section located out of direct alinement with the girder sections so as to provide a gap between the two said sections, supporting and guide wheels for one girder section for sustaining it upon two of the tracks at one side of the machine, separate supporting and guiding wheels for the other section for supporting it upon the tracks on the other side of the machine, feeding devices upon the two girder sections for feeding a sheet of metal longitudinally in a direction from one girder section to the other girder section, and manually controlled means extending to the platform for operating both the feeding means for the sheet and also for propelling the two girder sections and platform simultaneously along the guide tracks, whereby the sheet may be fed transversely to the machine and the carriage structure fed to and from the machine in a direction transversely to the feeding of the sheet upon the carriage, and manually controlled means for adjusting the sheet feeding means vertically whereby the level of the sheet in respect to the machine may be slightly varied.

10. A machine for operating upon sheet metal, and a plurality of parallel guide tracks part of which are arranged at one side of the machine and part at the other side, in combination with a long carriage structure extending laterally upon both sides of the machine and consisting of two girder sections connected by a platform section located out of direct alinement with the girder sections so as to provide a gap between the two said sections, supporting and guide wheels for one girder section for sustaining it upon two of the tracks at one side of the machine, separate supporting and guiding wheels for the other section for supporting it upon the tracks on the other side of the machine, feeding devices upon the two girder sections for feeding a sheet of metal longitudinally in a direction from one girder section to the other girder section, and manually controlled means extending to the platform for operating both the feeding means for the sheet and also for propelling the two girder sections and platform simultaneously along the guide tracks, whereby the sheet may be fed transversely to the machine and the carriage structure fed to and from the machine in a direction transversely to the feeding of the sheet upon the carriage, and manually controlled means for adjusting the sheet feeding means vertically whereby the level of the sheet in respect to the machine may be slightly varied.

11. A machine for operating upon sheet metal, and a plurality of parallel guide tracks part of which are arranged at one side of the machine and part at the other side, in combination with a long carriage structure extending upon each side of the machine and supported thereat on the guide tracks said carriage having a gap to fit around the machine and provided with an operator's platform, manually controlled means at the operator's platform for adjusting the carriage transversely of its length upon the guide tracks, means at each side of the gap of the machine and carried by the long carriage for supporting a long sheet of metal, manually controlled devices on and moving with the carriage and located at the operator's platform for feeding the sheet longitudinally of the length of the carriage across the machine, and means extending from the operator's platform for controlling the operation of the machine which operates upon the sheet metal irrespective of the position of the carriage relatively to the machine.

12. A machine for operating upon sheet metal, and a plurality of parallel guide tracks part of which are arranged at one side of the machine and part at the other side, in combination with a long carriage structure extending upon each side of the machine and supported thereat on the guide tracks said carriage having a gap at its side to fit about the machine, manually controlled means for adjusting the carriage transversely of its length upon the guide tracks, a plurality of wheels at each side of the machine and carried by the long carriage in fixed bearings for supporting a long sheet of metal, manually controlled devices on the carriage for feeding the sheet longitudinally of the length of the carriage.

6
across the machine, and manually controlled means to vary the level of the sheet where it passes across the machine said means comprising additional feeding wheels supported upon the carriage at each side of the gap thereof and devices for imparting slight vertical adjustments to said wheels.

In testimony of which invention, I hereunto set my hand
